FRANZ CECKA, OF CHEMNITZ, GERMANY, ASSIGNOR TO THE FIRM OF SCHUBERT & SALZER MASCHINENFABRIK, AKTIENGESELLSCHAFT, OF CHEMNITZ, GERMANY.

KNITTED GOODS AND THE METHOD OF MAKING THE SAME.

1,228,648.

Specification of Letters Patent.

Patented June 5, 1917.

Application filed September 8, 1914. Serial No. 860,642.

To all whom it may concern:

Be it known that I, FRANZ CECKA, a citizen of the German Empire, residing at Chemnitz, in the Kingdom of Saxony, Germany, have invented certain new and useful Improvements in Knitted Goods and the Method of Making the Same; and I do hereby declare the following to be a full, clear, and exact description of the invention, such 5 as will enable others skilled in the art to which it appertains to make and use the same, reference being had to the accompanying drawing, and to letters or figures of reference marked thereon, which form a part of this specification.

10 My invention relates to improvements in knitted goods and the method of making the same. The object of the improvements is to provide a method of making knitted goods 20 in which loops are widened over two or more needles, and in which no holes are produced in the fabric by the widening of the loops.

In making knitted goods the loops are ordinarily widened by shifting a number of 25 loops laterally a distance corresponding to the pitch of the needles, whereby the needle located at the beginning of the widened portion becomes disengaged, and a hole is produced in the fabric which however is not objectionable, and can even be removed by 30 hanging on the disengaged needle the loop of the previous row of loops. Heretofore it was not possible to widen a number of adjacent loops over two or more needles for the 35 reason that at some part a hole was produced which extends over two loops, so that when continuing the work it was impossible to take up the thread for forming further loops. At such places so called ladders were 40 formed.

For certain sorts of goods such loops may be satisfactory. But in smooth fabrics they are objectionable and must be avoided.

However, in some cases the desired form 45 is not obtained by widening over single needles and it is desirable to widen two or more loops.

The object of the improvements is to provide a method by means of which the loops 50 can be widened over two or more needles without producing ladders. With this object in view my invention consists in interrupting the series of widened loops in such a way that before the last widening needle 55 loops are omitted in widening.

For example, if it is desired to widen over two or three needles, a needle must be omitted before the first row, and thereafter a further widening needle must be added.

For the purpose of explaining the invention 60 an example of a fabric made by my improved method has been shown in a dia-grammatical way in the accompanying drawing.

As appears from the example shown in the 65 drawing the formation of ladders is avoided, because no hole is made which extends over two needles, but at two places which are separated by a loop holes of the breadth of one loop each are formed.

In the example shown in the drawing 70 widening is to be performed on the part of the fabric which is at the right of the line A—B, which part contains the loops 1, 2, 3, 4, 5, 6, 7. The widening apparatus is 75 made in such a way, that the widening needle *a* so acts on the loop 1, that in the position of the loop 2 there is no widening needle, and that in the position of the third and following loops before all the further 80 loops to be widened widening needles *b*, *c*, *d*, *e*, *f* are located. If after completing the series I the loops are widened over two needles, loop 1 gets into the position of loop 3, loop 3 into the position of loop 5, and 85 each of the following loops is shifted to the right a distance corresponding to the double pitch of the needles, as appears from row II.

As loop 2 has not been widened the hole 90 which would otherwise be produced at the left of widened loop 1 and extend over two needles is reduced to a hole which extends only over one needle, as is shown in row II at 1, a second hole being produced at the right of the widened loop 1, as is shown in 95 row II at 4. As appears from the diagram, when continuing the knitting operation at the height of each needle, loops are formed for the further loops to be produced in row III. In row IV the widening operation 100 has begun at loop 3, so that the holes are passed over to the right according to the increase in the breadth of the fabric, as is shown in row IV, at 3 and 6.

The holes which are thus produced can 105 be closed if desired by known methods, for example by pulling out a loop from the previous row and hanging the same on the corresponding needle of the succeeding row.

An important feature of my invention 110

consists in that the holes which are produced by the widening operation are closed or reduced to the distance of two consecutive needles by the loops which have not been widened.

5 I claim herein as my invention:

1. The method of producing on a knitting machine, a knitted fabric having at least one widened portion which comprises regularly 10 knitting at least one row of loops, widening at least one succeeding row of loops by transferring a group of loops for at least two needle divisions, and reducing the gap produced at the commencement of the said 15 transference to the width of one needle division by excluding from said transference at least the second loop within said group whereby the loops of the succeeding row are locked against raveling.
2. The method of producing on a knitting machine, a knitted fabric having at least 20 one widened portion which comprises regularly knitting at least one row of loops,

widening at least one succeeding row of loops by uniformly transferring a group of 25 loops for at least two needle divisions, and reducing the gap produced at the commencement of the said transference to the width of one needle division by excluding from said transference at least the second 30 loop within said group whereby the loops of the succeeding row are locked against raveling.

3. A knitted fabric comprising rows of successively knitted loops, a group of successive loops excluding at least one loop being widened out the distance of at least two loops, the excluded loop locking the loops of the succeeding row against raveling.

In testimony that I claim the foregoing 40 as my invention, I have signed my name in presence of two subscribing witnesses.

FRANZ CECKA.
